UNITED STATES PATENT OFFICE

EDWARD E. RICE, OF IRVINE, KENTUCKY

COIN CONTROLLED LIQUID VENDING APPARATUS

Application filed July 26, 1930. Serial No. 470,955.

This invention relates to liquid vending apparatus, and more particularly to apparatus of this type that are especially adapted for vending gasoline and embody a stand, a measuring chamber mounted on the upper end of the stand, a pump arranged within the lower end of the stand and adapted to be operated by a rocker lever to raise the gasoline to a measuring chamber embedded in the ground, and a hose communicating with the measuring chamber and adapted to convey the gasoline therefrom to the storage tanks of automobiles.

The invention has for one of its objects to provide an apparatus of this character which shall embody novel, simple and highly efficient means adapted to normally lock the rocker lever against operation and adapted to be actuated through the medium of a coin to effect the release of the rocker lever, to the end that the apparatus may be used for the purpose of dispensing gasoline without the services of an attendant.

The invention has for a further object to provide an apparatus of the character stated wherein the coin controlled means shall embody a bolt mounted in the stand for movement into an active position and into an inactive position, means yieldingly holding the bolt in active position, a keeper mounted on the rocker lever for movement into an angular position and into an axial position with respect to the bolt and adapted to be engaged by the bolt in both positions thereof, means yieldingly holding the keeper in said first position, means carried by the rocker lever and connected to the keeper for moving the keeper into said second position, and a chute for directing a coin in the path of the keeper during its movement from said first to said second position, the keeper carrying the coin between itself and the bolt and effecting through the medium of the coin the movement of the bolt into inactive or keeper releasing position.

The invention has for a further object to provide an apparatus of the character stated which shall embody a valve for controlling the communication between the measuring chamber and the hose, and which shall also embody means connecting the valve to the

bolt, to the end that the bolt will, when in active position, hold the valve opened and when in inactive position hold the valve closed, and thus require the releasing of the keeper and its engagement by the bolt before the contents of the measuring chamber may be withdrawn.

The invention has for a further object to provide an apparatus of the character stated through the medium of which different quantities of gasoline may be vended.

The invention has for a still further object to provide an apparatus of the character stated wherein the coin controlled means shall be adapted to be rendered inactive to lock the rocker lever, and wherein the means connecting the valve to the bolt shall be adapted to be rendered inactive, to the end that an attendant may operate the rocker lever and valve without inserting a coin in the chute.

The invention is hereinafter more fully described, and claimed and illustrated in the accompanying drawings, wherein:

Figure 1 is a view in side elevation of a liquid vending apparatus embodying my invention;

Figure 2 is a sectional view taken on the vertical plane indicated by the line 2-2 of Figure 1;

Figure 3 is a view partly in section and partly in elevation, on an enlarged scale, of one of the pump rocker levers and the coin controlled mechanism therefor;

Figure 4 is a sectional view taken on a plane extending vertically and centrally through the coin chute and slug detecting means of one of the rocker levers;

Figure 5 is a sectional view taken on a vertical plane extending centrally and transversely through the coin controlled mechanism of one of the rocker levers with the keeper in its normal and locked position, a coin being shown in the guides of the coin chute and in the groove of the bolt;

Figure 6 is a view similar to Figure 5 with the keeper in bolt retracting position;

Figure 7 is a sectional view taken on a vertical plane extending centrally and longitudinally through the coin controlled mecha-

nism with the parts in the position in which they are shown in Figure 6;

Figure 8 is a sectional view taken on the horizontal plane indicated by the line 8—8 of Figure 7;

Figure 9 is a sectional view taken on a plane extending vertically and centrally through the discharge valve of one of the measuring compartments;

16 Figure 10 is a view partly in side elevation and partly in vertical section of the means for detachably connecting one of the valve rod sections together;

15 Figure 11 is a sectional view taken on the horizontal plane indicated by the line 11—11 of Figure 2;

20 Figure 12 is a sectional view illustrating the position that the keeper assumes when rocked into concentric relation to the bolt without first inserting a coin, and

Figure 13 is a sectional view taken on a vertical plane extending centrally and transversely through the rocker lever steadyng means.

25 Referring in detail to the drawings, 1 designates a stand, which comprises a hollow column 2 mounted upon a hollow base 3, and a measuring chamber 4 mounted upon the upper end of the column. The measuring chamber 4 is preferably made of glass, and is separated by a vertical partition 5 into compartments 4^a and 4^b. The measuring chamber 4 is provided with level indicating lines 6, and these lines are marked from 1 to 14, as indicated at 7, in order to enable the purchaser to determine whether the chamber contains the amount of gasoline he wishes to purchase.

40 Pumps 8 and 9, which may be of any well known or appropriate construction, are located in the base 3, and are adapted to be operated by rocker levers 10 and 11, respectively. The rocker levers 10 and 11 are fixed to and extend upwardly from the piston actuating shafts 12 and 13 of the pumps 8 and 9. A pipe 14 extends from the intake port of the pump 8 to a storage tank 15 adapted to be embedded in the ground below the base 3, and a pipe 16 extends from the discharge port of the pump to the measuring compartment 4^a. A pipe 17 extends from the intake port of the pump 9 to the storage tank 15, and a pipe 18 extends from the discharge port of this pump to the measuring compartment 4^b. By operating the pumps 8 and 9 through the medium of their rocker levers 10 and 11, gasoline will be elevated from the storage tank 15 into the measuring compartments 4^a and 4^b.

60 A measuring tube 19 which is rotatably and slidably mounted in the stand 1 and extends from the measuring compartment 4^a to the storage tank 15, and a measuring tube 20 which is also slidably and rotatably mounted 65 in the stand and extends from the measuring

compartment 4^b to the storage tank, provide means by which the amount of gasoline that may be dispensed from either one or both of these compartments may be regulated and controlled. The measuring tubes 19 and 20 are provided with arms 21 and 22, respectively, through the medium of which they may be raised and lowered to position their upper ends at the required distance from the bottom of the measuring compartments 4^a and 4^b. 75

The arm 21 is adapted to be engaged in one of a vertical series of notches 23 formed in a bar 23^a located within the stand 1, and the arm 22 is adapted to be engaged in one of a vertical series of notches 24 formed in a bar 24^a in the stand, to secure the measuring tubes 19 and 20 in their adjusted positions. Access to the arms 21 and 22 may be gained through doors 25 on the column 2 and secured in closed position by locks 26, one only 85 of which is shown.

80 A delivery hose 27 extends from the measuring compartment 4^a, and a similar hose 28 extends from the measuring compartment 4^b. The upper or intake ends of the hose 27 and 28 are under the control of normally opened valves 29 and 30, respectively, and the lower or delivery ends of the hose are provided with nozzles 31 and 32, respectively, adapted to be inserted in the filler openings of gasoline storage tanks of automobiles. The nozzles 31 and 32 are similar, and each is provided with a normally closed valve 33. Levers 34, which are pivoted, as at 35, to the nozzles 31 and 32 and are connected, as at 36, to the valves 33, provide means by which these valves may be manually opened to permit the gasoline to flow from the hose 27 and 28 to the storage tanks of automobiles. The valves 33 are normally maintained in 105 closed position by springs not shown, with in the nozzles 31 and 32.

100 The rocker levers 10 and 11 are secured to the pump shafts 12 and 13 by brackets 37 which space them outwardly beyond the 110 shafts. The lower portions of the rocker levers 10 and 11 are located within the base 3, and the upper portions of the levers are located above the base. The base 3 is provided in its upper side with slots 38 through 115 which the rocker levers 10 and 11 extend and in which they have a snug fit. Closure plates 38^a and 39^a are provided for the slots 38 and 39, respectively, and these plates are connected to the levers 10 and 11, respectively. The closure plates 38^a and 39^a extend in opposite directions from the levers 10 and 11 and contact with the lower surface of the upper side of the base 3, such plates effecting the closure of the slots in any position of the levers and being adapted to prevent foreign matter from being inserted into the base through the slots. 125

120 Coin controlled means are provided for normally locking the rocker levers 10 and 11 130

against movement. These means are arranged within the base 3 and access thereto may be had only by way of doors 39 on the base and are secured in closed position by locks 40. Bearing yokes 41 of arcuate formation in elevation, are secured to and extend transversely of the rocker levers 10 and 11, and are provided with anti-friction elements 42. Bearing bolts 43 secured to and within the base 3, extend into the yokes 41, and are provided with anti-friction elements 44 which support rings 44a which in turn contact with the anti-friction elements 42. These parts are located above the pump shafts 12 and 13, and serve to balance the rocker levers 10 and 11 and insure their free movement when released for operation. The lower ends of the rocker levers 10 and 11 have secured thereto loops 45. The loops 45 extend downwardly from the rocker levers 10 and 11 and have secured to their lower ends weights 46 which constantly tend to move the rocker levers into vertical position.

Coin or check controlled means for the rocker lever 10 comprises a coin chute 47 which extends longitudinally through the rocker lever 10 and is fully open at its upper end to permit the insertion of a coin therein. Slotted guides 48 extending downwardly from the lower end of the coin chute 47, are open at their lower ends to permit the coin to be withdrawn downwardly from between the same, and are provided at said ends thereof with spring fingers 50 which prevent the accidental downward displacement of the coin therefrom, the fingers 50 being adapted to yield laterally to permit the coin to be forcibly moved downwardly from the guides.

This means also comprises a lock which includes a bolt 51 slidably mounted within the base 3 and a keeper 52 pivoted to the lower end of the rocker lever 10. The bolt 51 is of arcuate formation in elevation and is provided in its upper or convex side with a groove 53 of V-form in cross section. The bolt 51 is secured at its center to the upper end of a rod 54 which is mounted in a bracket 55 for vertical sliding movement. The bracket 55 is secured, as at 56, to and within the base 3.

Springs 57 carried by the bracket 55 and bearing at their lower ends against the bracket and at their upper ends against a collar 58 secured to the rod above the bracket, serve to yieldingly support the bolt 51 in active position. A head 59 secured to the rod 54 below the bracket 55 cooperates with the bracket to limit the movement of the bolt 51 by the springs 57. Brackets 60 are carried by the rocker lever 10, and have arms 60a secured, as at 61, to the lateral sides of the rocker lever and inclining downwardly and outwardly therefrom. The brackets 60 also

ward from the lower ends of their arms 60a.

The keeper 52 is arranged between the bracket arms 60a, and is provided at its ends with arms 62 which are connected to these bracket arms by pivots 63, to the end that the keeper may be rocked into an angular or lateral or concentric or axial position with respect to the bolt 51. The keeper 52 is normally supported in its angular position with respect to the bolt 51 by springs 64 which are secured to the keeper and to the bracket 60.

Hand levers 65 are pivoted, as at 66, to the lateral sides of the rocker lever 10 and extend upwardly from their pivots to points above the upper end of the rocker lever. Cranks 67 are fixed to the lower ends of the levers 65 and are connected by links 68 to arms 69 carried by the keeper 52. The connection between the keeper 52 and the levers 65 is such that, when the levers are gripped and moved in the direction of each other by the hand, the keeper 52 will be moved from its angular position with respect to the bolt 51 into its concentric position with respect to the bolt. During this movement of the keeper 52, the springs 65 are tensioned so that they will, when the lever 65 is released, return the keeper to its angular position with respect to the bolt 51.

Lugs 70 carried by the bolt 51, engage in recesses 71 of arms 72 on the keeper 52 to effect a locking connection between the bolt and keeper, and this connection between these parts locks the rocker lever 10 against movement. The bolt 51 is in locking engagement with the keeper 52 when the bolt is in raised position and the keeper is in both of its positions. To effect the release of the keeper, and thus permit the operation of the rocker lever 10, the bolt must be moved downwardly against the tension of its springs 57, and this is accomplished through the medium of a coin between the bolt and keeper. The keeper 52 is provided with a concave side, and said side thereof is provided with a groove 73 which is of V-form in cross section and which, when the keeper is in concentric relation to the bolt 51, registers with the groove 53 of the bolt. The keeper 52 during the rocking thereof into its concentric position with respect to the bolt 51, moves over the coin 75 between the guides 48 and spring fingers 50 and carries the coin between itself and the bolt. The coin 75 is now in the bolt groove 53 and keeper groove 73.

During the movement of the keeper 52, due to location of the coin 75 between it and the bolt 51, the bolt is moved downwardly by the coin far enough to carry the lugs 70 out of engagement with the arms 72, and thus release the rocker lever 10 for operation. The lever is operated through the medium of the hand levers or grips 65, and during its operation, the coin moves in the bolt groove 53.

53 and keeper groove 73. After the desired quantity of gasoline has been elevated into the measuring container 4a, the grips 65 are released, with the result that the keeper 52 is moved back into its angular position with respect to the bolt 51 by the springs 64. During this movement of the keeper 52, the coin 75 is discharged from between the keeper and bolt 51 and falls into a receptacle, not shown, within the base 3. If the rocker lever 10 is not in vertical position when the grips 65 are released, the weight 46 will carry it into this position and when it reaches this position, the lugs 70 on the bolt 51 engage the arms 72 on the keeper 52, with the result that the rocker lever 10 is again locked against operation.

Permanent magnets 77 carried by the rocker lever 10 serve to deflect into a tube 78 any iron, steel or nickel-plated and other magnetic metal slugs that may be inserted in the coin chute 47. The tube 78 is carried by the rocker lever 10, and communicates at its upper end with the coin chute 47. The lower end of the tube 78 extends through the lateral side of the rocker lever 10 at a point above the lower end of the coin chute so as to discharge the slugs into the base 3.

Should a lead slug be inserted in the chute 47, it would pass to the lower end of the coin chute but would not effect the unlocking of the rocker lever 10 due to the fact that it would be crushed by the keeper 52 during its movement into concentric position with respect to the bolt 51. The crushed slug would be discharged from between the bolt 51 and keeper 52 after the release of the grips 65 and during the return of the keeper to its normal or angular position with respect to the bolt.

The coin controlled means for the rocker lever 10 is adapted to be actuated through the medium of a twenty-five cent piece for the purpose of freeing this rocker lever for operation. Coin controlled means are provided for the rocker lever 11, and this means is adapted to be actuated through the medium of a fifty-cent piece to free this rocker lever for operation. The coin controlled means for the rocker lever 11 are similar to that of the rocker lever 10 with the exception that the lugs on the bolt thereof are longer and with the exception that the arms on the keeper thereof are curved on a greater radius, to the end that this bolt will have to be moved further downwardly in order to effect the release of the keeper.

The valve 29 comprises a cylindrical casing 79 arranged in the measuring compartment 4a at the lowest point therein, and having an annular intake port 80 which communicates with the measuring compartment and with which the upper or intake end of the hose 27 communicates. A cylindrical plug 81 is mounted in the casing 79 for vertical sliding movement, and is provided with an opening

or annular groove 82 which, when the plug is in opened position, communicates with the intake port 80 of the casing.

A rod 83 extends downwardly from the plug 81 and is pivotally connected at its lower end, as at 83a, to one end of a lever 84. The lever 84 is pivotally connected between its ends to one wall of the base 3, as at 85, and has its other end pivotally connected, as at 86, to the bolt 51. The connection between the plug 81 and the bolt 51 is such that the plug is supported in opened position by the bolt and is moved downwardly into closed position by the bolt when the latter is moved downwardly to release the rocker lever 10. The valve 30 is similar in construction to the valve 29 and is connected in a similar manner to the bolt 51 controlling the rocker lever 11.

In practice, the measuring tube 19 is adjusted to adapt the measuring compartment 4a to hold twenty-five cents worth of gasoline, and the measuring tube 20 is adjusted to adapt the measuring compartment 4b to hold fifty cents worth of gasoline, and thereafter these tubes are secured in their adjusted positions and the doors 26 closed and locked. The doors 39 are also locked, and in view thereof, a coin must be employed to effect the release of either the rocker lever 10 or the rocker lever 11 to enable gasoline to be pumped from the storage tank 15 to either the measuring compartment 4a or the measuring compartment 4b. If the automobilist wishes to purchase twenty-five cents worth of gasoline, he inserts a twenty-five cent piece in the coin chute 47 of the rocker lever 10, while if he wishes to purchase fifty cents worth of gasoline, he inserts a fifty cent piece in the coin chute of the rocker lever 11.

After the insertion of the coin, the grips 65 of the handle lever in which the coin has been inserted are grasped and moved in the direction of each other. This results in the keeper 52 of such rocker lever being moved into concentric relation with respect to the bolt 51 with which it is associated. At the same time, the coin is moved from the coin chute by the keeper 52 and into a position between the keeper and bolt 51, effecting the downward movement of the bolt and the consequent releasing of the rocker lever, the downward movement of the bolt closing the valve plug 81 connected thereto. The lever is now rocked to operate the pump to which it is connected, and the operation of the pump elevates the gasoline into the measuring compartment with which the pump communicates. When the amount of gasoline that the measuring compartment will hold has been elevated thereinto, the grips 65 are released, with the result that the keeper 52 is released for movement by its springs 64 into angular position with respect to its bolt 51. At the same time, the coin is discharged from be-

6 between the bolt 51 and keeper 52 and falls
 into a receptacle, not shown, provided there-
 for and placed in the base 3. The bolt 51 is
 now free to move upwardly, and this upward
 movement of the bolt moves the valve plug
 10 81 connected therewith into opened position
 so that the gasoline may pass to the hose
 connected with the measuring compartment.
 After the nozzle of the hose has been inserted
 15 in the filler opening of the storage tank of
 the automobile, the valve of the nozzle is
 opened so as to permit the gasoline to flow
 into the storage tank. This upward move-
 ment of the bolt 51 results in the locking of
 20 the rocker lever, so that it cannot be again
 operated until another coin is inserted in its
 coin chute.

25 As the apparatus enables the dispensing of
 gasoline without the services of an attendant,
 it is especially adapted for use after the clos-
 ing of service stations. To enable it to be
 30 operated by an attendant while the service
 station using it is open, the coin controlled
 means thereof are rendered ineffective by se-
 curing the bolts 51 in retracted or keeper re-
 35 leasing position. This is accomplished
 through the medium of levers 87 which are
 pivoted, as at 88, within the base 3 and are
 provided with hooks 89 for engagement with
 40 loops 90 carried by the lower ends of the rods
 54, the hooks being adapted to be engaged
 with the loops after the bolts 51 have been
 moved downwardly into retracted position,
 and they may be moved in this position manu-
 45 ally after the doors 39 have been unlocked
 and opened.

50 The valve rods 83 are of sectional forma-
 tion, the upper sections 83^a thereof being se-
 cured to the valve plugs 81, and the lower sec-
 tions 83^b thereof being secured to the levers
 55 84. The valve rod sections 83^a and 83^b have
 their adjacent ends connected by hooks 91
 carried by the lower ends of the valve rod
 sections 83^a and detachably engaged with
 60 loops 92 carried by the upper ends of the
 valve rod sections 83^b. The hooks 91 are held
 against accidental disconnection from the
 loops 92 by guards 93 which are pivotally con-
 nected to the loops for movement into and out
 65 of position across their throats. Arms 94 are
 carried by the guards 93 and are adapted to be
 engaged by loops 95 carried by the valve rod
 sections 83^a in order to releasably secure the
 guards in active position. After the guards
 70 93 have been swung into inactive position,
 the valve rod sections 83^b may be disconnected
 from the valve rod sections 83^a, with the re-
 sult that the valve plugs 81 may be free for
 operation by the attendant.

75 To permit this operation of the valve plugs
 81, the handle rods 96 are detachably secured
 to the valve rod sections 83^a and extend
 through the door openings in the column 2.
 The valve rod sections 83^b are supported in
 80 upright position by brackets 97 which are

secured to and within the column 2 and with
 which these valve rod sections are slidably
 associated. When the apparatus is in condi-
 tion for operation by coins, the rods 96 are
 removed and the doors 26 closed and locked. 70

While I have described the principle of the
 invention, together with the structure which
 I now consider the preferred embodiment
 thereof, it is to be understood that the struc-
 ture shown is merely illustrative and that
 75 such changes may be made, when desired, as
 fall within the scope of the invention as
 claimed.

I claim:—

80 1. A liquid vending apparatus, including a
 pump, a rocker lever for operating the pump,
 a bolt mounted for movement into an active
 and inactive position, means yieldingly hold-
 85 ing the bolt in active position, a keeper mount-
 ed on the rocker lever for movement into an
 angular and axial position with respect to the
 bolt and engaged by the bolt in both of said
 positions, means yieldingly holding the 90
 keeper in said first position, means operable
 to move the keeper from said first to said
 second position, and means for directing a
 coin between the keeper and bolt during the
 95 movement of the keeper from said first to said
 second position, the coin permitting the
 keeper during said movement thereof to move
 the bolt into inactive or keeper releasing pos-
 100 ition.

105 2. A liquid vending apparatus, including a
 pump, a rocker lever for operating the pump,
 a bolt mounted for movement into an active
 and inactive position and provided with a
 longitudinally grooved convex face, means
 110 yieldingly holding the bolt in active position,
 a keeper provided with a longitudinally
 grooved concave face and mounted on the
 rocker lever for movement into an angular
 115 position and an axial position with respect to
 the bolt, means yieldingly holding the keeper
 in said first position, means operable for mov-
 ing the keeper from said first to said second
 120 position, and means for directing a coin into
 the grooves of the bolt and keeper during the
 movement of the keeper from said first to said
 second position, the keeper during its move-
 ment into said second position forcing the
 125 bolt through the medium of the coin into in-
 active or keeper releasing position.

130 3. A liquid vending apparatus, including
 a pump, a rocker shaft for operating the
 pump, a lever fixed at one end to the shaft,
 a bolt mounted for movement into an active
 and inactive position, means yieldingly hold-
 135 ing the bolt in active position, a keeper
 mounted on the rocker lever for movement
 into an angular position and an axial posi-
 tion with respect to the bolt and engaged by
 the bolt in both of said positions, means
 yieldingly holding the keeper in said second
 position, grip levers secured to the free end
 of said first lever and connected to the keeper 136

to cause the keeper to be moved into said second position when they are operated, and a chute carried by said first lever and adapted to direct a coin in the path of the keeper during its movement from said first to said second position, the keeper during its movement into said second position moving through the medium of the coin the bolt into inactive or keeper releasing position.

4. A liquid vending apparatus, including a pump, a rocker shaft for operating the pump, a lever fixed at one end to the shaft, a bolt mounted for movement into an active and inactive position, means yieldingly holding the bolt in active position, a keeper mounted on the rocker lever for movement into an angular position and an axial position with respect to the bolt and engaged by the bolt in both of said positions, means yieldingly holding the keeper in said second position, grip levers secured to the free end of said first lever and connected to the keeper to cause the keeper to be moved into said second position when they are operated, a chute carried by said first lever and adapted to direct a coin in the path of the keeper during its movement from said first to said second position, the keeper during its movement into said second position moving through the medium of the coin the bolt into inactive or keeper releasing position, the keeper after being released and moved into said first position being adapted to be engaged by the bolt when said first lever is in a predetermined position with respect to the bolt, and means constantly tending to move said first lever into such position.

5. A liquid vending apparatus, including a pump, a rocker lever for operating the pump, a bolt mounted for movement into an active and inactive position, the bolt moving in the direction of the lever while moving into said first position and moving in a direction away from the lever while moving into said second position, means normally holding the bolt in said first position, a keeper mounted on the lever for movement into an angular and axial position with respect to the bolt and engaged by the bolt in both of said positions, means normally holding the keeper in said first position, means carried by the lever and connected to the keeper for moving the keeper into said second position, and means adapted to direct a coin in the path of the keeper during its movement from said first to said second position, the keeper during its movement to said second position moving the bolt through the medium of the coin into inactive or keeper releasing position.

6. A liquid vending apparatus, including a pump, a rocker lever for operating the pump, a bolt mounted for movement into an active and inactive position, the bolt moving in the direction of the lever while moving into active position and moving in a direc-

tion away from the lever while moving into inactive position, means carried by the lever for directing a coin against the bolt, a keeper mounted on the lever for movement into an angular position and an axial position with respect to the bolt and engaged by the bolt when in both of said positions, the keeper being adapted to engage a coin on the bolt and move the bolt into inactive position through the medium of the coin while being moved into said second position, and means yieldingly holding the keeper in said first position.

7. A liquid vending apparatus, including a pump, a rocker lever for operating the pump, a bolt mounted for movement into an active and inactive position, the bolt moving in the direction of the lever while moving into active position and moving in a direction away from the lever while moving into inactive position, means carried by the lever for directing a coin against the bolt, a keeper mounted on the lever for movement into an angular position and an axial position with respect to the bolt and engaged by the bolt when in both of said positions, the keeper being adapted to engage a coin on the bolt and move the bolt into inactive position through the medium of the coin while being moved into said second position, a slug detector carried by the lever, and means yieldingly holding the lever in said first position.

8. A liquid vending apparatus, including a pump, a rocker lever for operating the pump, a bolt mounted for movement into an active and an inactive position, the bolt moving in the direction of the lever while moving into active position and in a direction away from the lever while moving into an inactive position, means yieldingly holding the bolt in active position, brackets carried by the lever, a keeper having arms pivoted to the brackets so that the keeper may move into an angular position and into an axial position with respect to the bolt, means yieldingly holding the keeper in said first position, a coin chute extending longitudinally through the lever and provided at its lower end with guides adapted to direct a coin onto the bolt, the keeper being adapted during its movement into said second position to engage the coin and through the medium thereof move the bolt into inactive position, the bolt when in active position engaging the lever in both positions of the latter, other arms carried by the keeper, grip levers pivoted to the lever, and links connecting the grip levers to said other arms.

9. A liquid vending apparatus, including a stand, measuring chambers carried by the stand, pumps arranged within the stand and communicating respectively with the respective measuring chambers, rocker levers for operating the pumps, coin controlled means within the stand for each lever and normally securing the levers against operation, a hose

connected to each measuring chamber, valves controlling the flow of liquid from the measuring chambers to the hose, and means connecting the valves to said coin controlled means so that said means may maintain the valves open when in lever locking condition and maintain the valves closed when in lever releasing position.

10. A liquid vending apparatus, including a stand, measuring chambers carried by the stand, pumps arranged within the stand and communicating respectively with the respective measuring chambers, rocker levers for operating the pumps, coin controlled means within the stand for each lever and normally securing the levers against operation, a hose connected to each measuring chamber, valves controlling the flow of liquid from the measuring chambers to the hose, means connecting the valves to said coin controlled means so that said means may maintain the valves open when in lever locking condition and maintain the valves closed when in lever releasing position, means for rendering the coin controlled means ineffective to lock the levers, the means connecting the valves to the coin controlled means including a sectional rod, and elements detachably connecting the rod sections, the rod sections being adapted to be freed from connection with each other when the coin controlled means is rendered ineffective, and handles detachably secured to certain of said rod sections.

11. A liquid vending apparatus, including a stand, a measuring chamber on the stand, a pump communicating with the chamber, a rocker lever for operating the pump, coin controlled means arranged within the stand and normally securing the lever against operation and adapted to be actuated to effect the release of the lever, a hose communicating with the measuring chamber, a valve controlling communication between the measuring chamber and hose, and means connecting the valve to the coin controlled means so that the latter will hold the valve open when in lever locking condition and closed when in lever releasing condition.

12. A liquid vending apparatus, including a stand, a measuring chamber on the stand, a pump communicating with the chamber, a rocker lever for operating the pump, coin controlled means arranged within the stand and normally securing the lever against operation and adapted to be actuated to effect the release of the lever, a hose communicating with the measuring chamber, a valve controlling communication between the measuring chamber and hose, means connecting the valve to the coin controlled means so that the latter will hold the valve open when in lever locking condition and closed when in lever releasing condition, a member carried by the lever and provided with anti-friction elements, and a member carried by the stand

and provided with anti-friction elements contacting with said first anti-friction elements.

13. A liquid vending apparatus, comprising a measuring chamber, a pump communicating with the chamber, a rocker lever for operating the pump, members carried by the lever and stand and normally engaging each other to lock the lever against operation, one of said members being movable to free the other and the other of said members being movable to effect said movement of said first member through the medium of a coin, means for directing a coin between the members, and means by which said other member may be manually operated.

14. A vending apparatus including an operating lever, first and second members normally engaging each other to lock the lever against operation, means having a fixed position with respect to the lever and carrying said second member for movement in a direction to free said first member, means connecting said first member to the lever and supporting it for movement independently thereof to effect said movement of said second member through the medium of a check, means for directing a check between the members, and means by which said first member may be operated.

15. A vending apparatus including an operating element, first and second members normally engaging each other to lock said element against operation, means having a fixed position with respect to said element and carrying said second member for movement in a direction to free said first member, means connecting said first member to said element and supporting it for movement with respect thereto to effect said movement of said second member through the medium of a check, means for directing a check between said members, and means by which said first member may be operated.

16. A vending apparatus including an operating element, first and second members normally engaging each other to lock said element against operation, means having a fixed position with respect to said element and carrying said second member for movement in a direction to free said first member, means mounting said first member on said element for movement with respect thereto to effect said movement of said second member through the medium of a check, means for directing a check between said members, and means by which said first member may be operated.

In testimony whereof I hereunto affix my signature.

EDWARD E. RICE. 125
